UNITED STATES PATENT OFFICE.

HUGO TUECKMANTEL, OF IRVINGTON, NEW JERSEY, ASSIGNOR TO THE R. NEUMANN HARDWARE CO., A CORPORATION OF NEW JERSEY.

STAY-HINGE FOR BAG-FRAMES.

1,102,307.

Specification of Letters Patent.

Patented July 7, 1914.

Application filed February 10, 1914. Serial No. 817,758.

To all whom it may concern:

Be it known that I, HUGO TUECKMANTEL, a citizen of the United States, residing at Irvington, in the county of Essex and State of New Jersey, have invented certain new and useful Improvements in Stay - Hinges for Bag-Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in bag-frames; and this invention has reference, more particularly, to a novel construction of bag-frame and hinge-construction therefor, the hinge-members forming integral portions of the bag-frame sections, the ends of the frame-sections being peculiarly bent and pivotally connected, and the bent ends of the frame-sections forming stay-members which provide catch - portions for the engagement therewith of a spring-plate to retain the frame-sections in their open relation, but the said spring - plate being in separable sliding engagement with one of said catch-portions, to permit of the closing of the hinged frame-sections.

The present invention, therefore, has for its principal object to provide a novel and simply constructed bag-frame, the hinge-members of which form integral parts of the respective frame-sections thereof, and the hinge-members of which are of such construction that an efficient stay-hinge is provided, all of the parts being arranged in a manner so as to do away with the additional cost of construction in making independent hinges, and, furthermore, thereby avoiding the additional cost and labor in attaching such independent hinges to the bag-frame sections.

The invention has for its further object to provide a novel combined bag-frame and stay-hinge therefor for readily bringing the frame-sections into their opened relations and positively retaining them in their opened relations, but the parts of the hinge-construction being arranged in such a manner, so that the opened bag-frame sections can be easily and quickly closed without

any further operation on the part of the operator.

Other objects of the present invention not at this time more particularly enumerated will be clearly understood from the following detailed description of the said invention.

With the various objects of the present invention in view, the invention consists, primarily, in the novel combined bag-frame and hinge-connection hereinafter set forth; and, the invention consists, furthermore, in the details of the construction of the parts of the bag-frame and its hinge-connection more fully described in detail in the following specification, and then finally embodied in the clauses of the claim which are appended to and which form an essential part of this specification.

The invention is clearly illustrated in the accompanying drawings, in which:

Figure 1 is a plan view of a bag-frame and its hinge-connections made according to and embodying the principles of the present invention, the frame - sections being shown in their opened relation. Fig. 2 is a fragmentary side-elevation of one of the hinged portions of the bag-frame-sections, said view being made on an enlarged scale, and the parts being represented in their "stayed" open relation; and Figs. 3 and 4 are side elevations of the opposite sides of the hinge-connection, certain parts of the frame being omitted from said views, and the hinged portions represented in said Figs. 3 and 4 being shown in their closed or folded positions with relation to each other. Fig. 5 is a transverse section, taken on line 5—5 in said Fig. 2, looking in the direction of the arrow α .

Similar characters of reference are employed in all of the above described views, to indicate corresponding parts.

Referring now to the said drawings, the reference-character 1 indicates one style of complete bag-frame, the same in this case comprising two frame-sections which are pivotally connected by means of the hinge-connections made according to and embodying the principles of the present invention.

In the present form of bag-frame the reference-characters 2 and 3 indicate the side-sections, and 4 and 5 the outer and inner body-sections, respectively, of a bag-frame

of the style known as "English" or "sewed-in" frame, the side-sections and body-sections being connected by means of suitably constructed angle-irons or brackets, as 6.

5 As shown in the several figures of the drawings, the end-portions of the side-sections 2 are bent at right angles, as at 7, so as to lie in vertical planes at right angles to the horizontal plane of the upper face of 10 said side-section 2. In like manner, the end-portions of the side-sections 3 are also bent at right angles, as at 8, so as to lie in vertical planes at right angles to the horizontal plane of the upper face of said side-section 15 3. Thus, the frame-sections of the bag-frame are provided at their respective end-portions with pivot-ears or lugs 7 and 8, which are integrally connected with the respective side-sections of the bag-frame, and 20 extend longitudinally from the said end-portions of the side sections, substantially in the manner shown. The said pivot-lugs or ears 7 and 8 thus formed, are respectively provided with the perforations 9 and 10, 25 for the reception of a pivot-pin 11, when the two ears or lugs 7 and 8 are brought into hinged registration with each other. A suitable separating plate or washer, as 12, may be placed between the two ears or lugs 7 30 and 8, and upon the pivot-pin 11, so as to insure a perfect pivotal relation between the said ears or lugs 7 and 8 as will be evident. The upper marginal edge-portions of the said ears or lugs 7 and 8 are, preferably, 35 convexly curved, as at 13 and 14, but it will be evident that they may be of any other desired marginal configuration. Upon their lower marginal edge-portions, the said ears or lugs 7 and 8 are respectively provided 40 with retaining depressions 15 and 16, preferably of concave conformation, as shown, and for the purposes to be presently more fully set forth.

The marginal edge-portions 13 and 15 of 45 the ear or lug 7, and the corresponding edge-portions 14 and 16 of the ear or lug 8, provide suitably-shaped nosings, as 17 and 18. The separating plate 12, as will be seen from Fig. 3 of the drawings, may also be provided 50 with a concave marginal edge-portion, as 19, which is in alinement with and conforms to the marginal depression 16 of the ear 8, although it will be understood, that for the purposes of the present invention, this concave marginal edge-portion 19 of the separating plate is not necessary, and the said plate may be of any other suitable marginal configuration.

Suitably secured upon the under surface 55 of the side-section 3 of the bag-frame, by means of rivets 20, or other suitable fastening means, is a spring-plate 21, having its forward end-portion 22 made with a curved engaging member, as 23, of the general con- 60

stantially to the shape of the concave depression 16 of the ear or lug 8, and with which the said member 23, when the frame-sections of the bag-frame, whether in their opened or closed relations, is in registration, substantially in the manner indicated in the several figures of the drawings. The said spring-plate 21 is of such width, so that, when the bag-frame sections are brought into their opened relation, the convex surface of the 70 engaging member 23 will ride upon a portion of the convex marginal edge 13 of the ear or lug 7, and over the nosing 17 of said lug or ear 7, the spring-action of the said plate 21 suddenly forcing the said engaging member 23 with a perceptible snap into its separable holding or retaining engagement with the retaining depression 15 of the pivot-car or lug 7, as will be readily understood from an inspection of Fig. 2 of the 80 drawings, the parts thus acting in the manner of a hinge-stay for positively holding open the frame-sections and the mouth of the bag-body secured to the said frame-sections.

From the foregoing description of the present invention, it will be clearly evident, that a neat and simply constructed bag-frame has been produced, the hinged connections of which form integral parts of the respective frame-sections so that a strong and efficient stay-hinge for bag-frames is also provided; and, furthermore, a better and much more neatly finished hinge-connection is the result, there being no unsightly obstructions or raised parts which prevent a neat finish of the usual leather coverings employed with bag-frames, and especially with the styles of frames known as "English" or "sewed-in" frames.

Of course, I am aware that some changes may be made in the general arrangements and combinations, as well as in the shapes of the several parts without departing from the scope of the present invention as set forth in the foregoing specification, and as defined in the clauses of the claim which are appended to and which form an essential part of the said specification. Hence, I do not limit my present invention to the exact 115 arrangements and combinations of the various parts as described in the foregoing specification, nor do I confine myself to the exact details of the construction of the said parts, as illustrated in the accompanying 120 drawings.

I claim:—

1. A bag frame comprising a pair of frame-sections, each frame-section being provided with registering hinge-members 125 forming integral portions of the said frame-sections, said hinge-members being in the form of perforated ears bent at right angles from the end-portions of the frame-sections and extending upwardly in vertical planes 130

- at right angles to the planes of the faces of said frame-sections and longitudinally of the end-members of the said frame-sections, said ears being provided in their lower marginal edge-portions with concave receiving depressions, a pivot-pin in the registering pivot-ears of said hinge-members, and a spring-plate secured to one of said frame-sections, said spring-plate having a curved 5 engaging member upon one of its end-portions normally in engagement with the marginal depression of one of said pivot-ears, said engaging member being adapted to be brought into slidable retaining engagement 10 with the marginal depression of the other of said pivot-ears.
2. A bag frame comprising a pair of frame-sections, each frame-section being provided with registering hinge-members 20 forming integral portions of the said frame-sections, said hinge-members being in the form of perforated ears bent at right angles from the end-portions of the frame-sections and extending upwardly in vertical planes 25 at right angles to the planes of the faces of said frame-sections and longitudinally of the end-members of the said frame-sections, said ears being provided in their lower marginal edge-portions with concave receiving 30 depressions, a pivot-pin in the registering pivot-ears of said hinge-members, a spring-plate secured to one of said frame-sections, said spring-plate having a curved engaging member upon one of its end-portions normally in engagement with the marginal depression of one of said pivot-ears, said engaging member being adapted to be brought 35 into slidable retaining engagement with the marginal depression of the other of said pivot-ears, and a perforated separating plate 40 mounted upon said pin and between the registering pivot-ears, the said plate being provided with a concave marginal edge-portion conforming substantially to the configuration of the concave receiving depressions of the pivot ears, substantially as and for the purposes set forth.

3. A bag frame comprising a pair of frame-sections, each frame-section being provided with registering hinge-members 45 forming integral portions of the said frame-sections, said hinge-members being in the form of perforated ears bent at right angles from the end-portions of the frame-sections and extending upwardly in vertical planes 50 at right angles to the planes of the faces of said frame-sections and longitudinally of the end-members of the said frame-sections, said ears being provided in their lower marginal edge-portions with concave receiving 55 depressions, a pivot-pin in the registering pivot-ears of said hinge-members, a spring-plate secured to one of said frame-sections, said spring-plate having a curved engaging member upon one of its end-portions normally in engagement with the marginal depression of one of said pivot-ears, said engaging member being adapted to be brought 60 into slidable retaining engagement with the marginal depression of the other of said pivot-ears, and a perforated separating plate 65 mounted upon said pin and between the registering pivot-ears, the said plate being provided with a concave marginal edge-portion conforming substantially to the configuration of the concave receiving depressions of the pivot ears, substantially as and for the purposes set forth. 70

In testimony, that I claim the invention set forth above I have hereunto set my hand 75 this 6th day of February, 1914.

HUGO TUECKMANTEL.
